UNITED STATES PATENT OFFICE.

HARRY STILLSON HART AND OTTO W. MEISSNER, OF CHICAGO, ILLINOIS,
ASSIGNORS TO RODGER BALLAST CAR COMPANY, OF CHICAGO, ILLINOIS,
A CORPORATION OF ILLINOIS.

DUMP-CAR.

SPECIFICATION forming part of Letters Patent No. 764,355, dated July 5, 1904.

Application filed July 11, 1903. Serial No. 165,199. (No model.)

To all whom it may concern:

Be it known that we, HARRY STILLSON HART and OTTO W. MEISSNER, citizens of the United States, residing at Chicago, in the county of 5 Cook and State of Illinois, have invented certain new and useful Improvements in Dump-Cars, of which the following is a specification.

This invention relates to that class of dump-cars known as "convertible" dump-cars—cars 10 which can be converted into several types of cars—viz., side-dump, center-dump, combined center and side dump, and flat-bottom gondola cars—all of which will more fully hereinafter appear.

15 The principal object of the invention is to provide a simple, economical, and efficient convertible dump-car.

Further objects of the invention will appear from an examination of the drawings and 20 the following description and claims.

The invention consists principally in a convertible dump-car in which there are combined a supporting-framework provided with downwardly and outwardly extending side dis- 25 charging-aprons, side boards pivotally secured at their upper edges to the supporting-frame-work, so that they may be opened and closed, a V-shaped hopper portion extending length- 30 wise of the car, with its apex at or near the longitudinal center, and swinging upper por-tions fulcrumed in the frame of the car and adapted to be moved to a position where they incline upwardly and outwardly to form the upper inclined portions of the V-shaped hop- 35 per and to be folded upwardly and inwardly into a second position to form, in connection with the side discharging-aprons, an A-shaped discharging-bottom for the car.

The invention consists, further and finally, in 40 the features, combinations, and details of construction hereinafter described and claimed.

In the accompanying drawings, Figure 1 is a side elevation of one end of a car as it appears when constructed in accordance with 45 these improvements; Fig. 2, a perspective detail of the angular locking-bar hereinafter described; Fig. 3, an end view of the car as

it appears when constructed in accordance with these improvements; Fig. 4, a cross-sectional view of the car, showing the various 50 parts arranged so as to form an A-shaped side-dumping car; Fig. 5, a cross-sectional view showing the parts arranged to form a V-shaped-hopper-bottom or center-dump car, and Fig. 6 a cross-sectional elevation showing the parts 55 arranged to form a flat-bottom gondola car.

In illustrating and describing these improvements we have only illustrated and will describe that which we consider to be new, taken in connection with so much as is old as 60 will properly disclose the invention to others and enable those skilled in the art to practice the same, leaving out of consideration other and well-known elements which, if set forth herein, would only tend to confusion, pro- 65 linity, and ambiguity.

In constructing a car in accordance with these improvements we provide a supporting-framework which has a discharging-apron *a* inclined downwardly and outwardly at each 70 side from end to end of the car. This supporting-framework has also a V-shaped hopper portion formed of one fixed section *b*, and a swinging section *c*, arranged lengthwise of the car and with its apex at or near the lon- 75 gitudinal center and between the car-trucks only, as shown particularly in Fig. 2. This supporting-framework is further provided with a pair of longitudinal sills *d*, one of which is arranged intermediate the V-shaped 80 hopper and each discharging-apron, to the frame portions of which they are connected by means of brace-rods *e*, which lead therefrom to the discharging-aprons. A second set of brace-rods *f* leads from said interme- 85 diate sills to the framework of the V-shaped hopper portion. A plurality of upwardly-extending side posts *g* is provided, attached at their lower edges, by means of gusset-plates *h* and brace-rods *i*, to the frame of the dis- 90 charging-aprons and connected together in an efficient manner at or near their upper edges by means of channel-beams *j*, which extend the entire length of the car. To these upper

channel-beams are pivotally connected side boards *k*, formed of a plurality of swinging sections, having their lower free edges arranged to be brought into meeting contact with the outer lateral edges of the discharging-aprons and form in connection therewith a side-dumping car and in connection with the **V**-shaped hopper a combined side and center dump car.

To operate the swinging section which forms a discharging-door for the **V**-shaped hopper, the usual rock-shaft *l* and chain mechanism *m* are provided and connected with such swinging section in the usual and ordinary manner. To lock the swinging side boards, however, an improved mechanism must be provided, and for this purpose we provide locking angle-bars *n*, one of which is arranged at or near each side of the car and by means of swinging **L**-bars *o* are pivotally secured to the supporting-framework of the car. Each of these **L**-bars—and there are several at each side of the car—have one portion forming a curved projecting finger *p*, which while the parts are being swung to their locking position, as hereinafter described, will first contact the lower edges of the swinging side boards before they are quite closed and force them into closed position, when the angle-bars, as shown particularly in Figs. 5 and 6, will finally contact and hold the doors closed in vertical position and at the same time form a seal to prevent discharge of comminuted material. To operate these locking angle-bars as desired, a rock-shaft *q* is rotatably mounted in bearings at or near the upper edge of each side of the car and provided with chain and rod mechanism *r*, connected with eye-bars *s* on the angle-bars, so that as such rock-shafts are rotated in one direction the angle-bars, with their closing-fingers, are moved toward locking position, while during the rotation of the rock-shaft in the opposite direction they are permitted to drop into the position shown in Fig. 4 to allow the side doors to be opened.

To form the convertible means, a pair of upper swinging sections *t* is provided and arranged so that they may be moved into one position, (see Fig. 5,) where they form the upper inclined portions of the **V**-shaped hopper, and into a second position, (see Fig. 4,) where they form the upper inclined portions of (and in connection with the discharging-aprons) an **A**-shaped side-dumping bottom. It is desirable to provide means for fulcruming and holding these upper swinging sections in their different positions. In order so to do, two sets of pivoted fulcruming-blocks are provided, one set, *v*, pivotally secured to the framework of the car adjacent to the **V**-shaped hopper portion, so as to form the fulcrums for the upper swinging sections when they are arranged in their **V**-shaped position, and a second set, *w*, pivotally secured in

position to the upper edges of the discharging-aprons, which form the fulcrum-blocks for the upper swinging sections when the same are arranged in their **A**-shaped position. These upper swinging sections extend from end to end of the car, and it is very desirable to provide some means to hold them in their **A**-shaped position; otherwise a heavy load in the car of coal, sand, rock, or the like might tend to displace them. To provide such means, removable end boards *x* are provided, one at each end of the car, having outer end stakes *y*, the lower ends of which are arranged to rest in metal pockets *z*. The inner faces of these removable end boards are provided with inwardly-extending cleats *10*, arranged in an **A**-shaped manner, so that they contact the ends of the upper swinging sections and prevent them from being displaced when the car is being loaded or in, fact at, any time until the end boards are removed. It will be understood, of course, that it is necessary to remove these end boards before the upper swinging sections can be moved from or into their **A**-shaped position. In Fig. 6 we have shown these upper swinging sections arranged in a third position—viz., a position in which they form the flat bottom of a gondola car, and in order to hold them in such position the upper edges of such swinging sections are provided with angle-blocks *11*, adapted to engage with a **U**-shaped locking-bar *12* at or near each end of the car. When the parts are in this position, as shown in Fig. 6, the meeting edges of the movable sections are locked in such **U**-shaped block and held against lateral displacement.

We claim—

1. In a car of the class described, the combination of a supporting-framework provided with upwardly-extending side boards formed of swinging sections pivoted at their upper edges, and locking angle-bars pivotally secured to the framework of the car near the sides thereof to engage with the lower free edges of the swinging doors to seal and hold the same in locked position, substantially as described.

2. In a car of the class described, the combination of a supporting-framework provided with upwardly-extending end boards and side boards formed of swinging sections pivoted at their upper edges, locking angle-bars pivotally secured to the framework of the car near the sides thereof to engage with the other edges of the doors and seal and hold the same in locked position, and projecting fingers on such angle-bars adapted to first contact the door and swing them into locking engagement with the angle-bars, substantially as described.

3. In a car of the class described, the combination of a supporting-framework, vertical end boards extending upwardly therefrom, side boards formed of a plurality of swinging

sections pivotally secured in position at their upper edges, a plurality of outwardly-extending finger mechanisms separately and pivotally secured to the car-frame and adapted to first contact the lower free edges of the swinging sections to force them to closed locked position, and bar mechanism mounted eccentric to the pivotal centers of the finger mechanism securing such finger mechanism together, substantially as described.

4. In a convertible dump-car, the combination of a supporting-framework provided with downwardly and outwardly extending side discharging-aprons, side boards pivotally secured at their upper edges to the supporting-framework so that they may be opened and closed, a **V**-shaped hopper portion extending lengthwise of the car with its apex at or near the longitudinal center, and swinging upper portions fulcrumed in the frame of the car and adapted to be moved to a position where they incline upwardly and outwardly to form the upper portions of the **V**-shaped hopper and to be folded upwardly and inwardly into a second position where they form in connection with the side discharging-aprons an **A**-shaped discharging-bottom for the car, substantially as described.

5. In a convertible dump-car, the combination of a supporting-framework provided with downwardly and outwardly inclined side discharging-aprons, swinging side boards pivotally secured in position so as to be opened and closed, a **V**-shaped hopper portion extending lengthwise of the car with its apex at or near the longitudinal center, and removable swinging upper portions fulcrumed in the frame of the car and adapted to be moved to one position where they incline upwardly and outwardly to form the upper inclined sides of the **V**-shaped hopper and to a second position where they extend upwardly and inwardly to form the upper inclined portions of and in connection with the discharging-aprons an **A**-shaped discharging-bottom for the car and to be removed and laid in a flat position to form the flat bottom of a gondola car, substantially as described.

6. In a convertible dump-car, the combination of a supporting-framework provided with downwardly and outwardly inclined side discharging-aprons extending from end to end of the car, a **V**-shaped hopper portion extending lengthwise of the car with its apex at or near the longitudinal center and between the car-trucks only, end boards for the car, swinging upper portions removably held in position extending from end board to end board of the car and adapted to be moved into one position where they incline upwardly and outwardly to form the upper portions of the **V**-shaped hopper to a second position where they incline upwardly and inwardly to form connection with the discharging-aprons an **A**-shaped discharging-bottom for the car and

to a third position where they form the flat bottom of a gondola car, and side boards pivotally secured in position, whereby they may be opened and closed as desired, substantially as described.

7. In a convertible dump-car, the combination of a supporting-framework provided with downwardly and outwardly inclined side discharging-aprons, a **V**-shaped hopper portion extending lengthwise of the car with its apex at or near the longitudinal center, upper swinging portions arranged to be swung into different positions where they form the upper inclined sides of the **V**-shaped hopper and the upper inclined portions of the **A**-shaped discharging-bottom, vertical side boards pivoted to the frame of the car at their upper edges and having their free edges adapted to meet the outer edges of the discharging-aprons, and means for locking the swinging side doors in closed position, substantially as described.

8. In a convertible dump-car, the combination of a supporting-framework provided with downwardly and outwardly inclined side discharging-aprons, a **V**-shaped hopper extending lengthwise of the car with its apex at or near the longitudinal center, upper swinging portions arranged to be swung into different positions where they form the upper inclined sides of the **V**-shaped hopper and the upper inclined portions of the **A**-shaped discharging-bottom, vertical side boards pivoted to the frame of the car at their upper edges and having their free edges adapted to meet the outer edges of the discharging-aprons, locking angle-bars pivotally secured to the framework of the car near the sides and provided with outwardly-extending fingers adapted to first contact the lower free edges of the swinging side boards and force them to closed position where the angle-bars hold them firmly closed, and means for swinging such angle-bars into locking position, substantially as described.

9. In a convertible dump-car, the combination of a supporting-framework provided with downwardly and outwardly inclined side discharging-aprons, a **V**-shaped hopper portion extending lengthwise of the car with its apex at or near the longitudinal center, upper swinging portions arranged to be swung into different positions where they form the upper inclined sides of the **V**-shaped hopper and the upper inclined portions of the **A**-shaped discharging-bottom, vertical side boards pivoted to the frame of the car at their upper edges and having their free edges adapted to meet the outer edges of the discharging-aprons, locking angle-bars pivotally secured to the framework of the car near the sides and provided with outwardly-extending fingers adapted to first contact the lower free edges of the swinging side boards and force them to closed position where the angle-bars hold them firmly closed, a rock-shaft, and chain mechanism

connected with the rock-shaft and with the locking angle-bars for moving such bars into locking position, substantially as described.

10. In a convertible dump-car, the combination of a supporting-framework provided with downwardly and outwardly inclined side discharging-aprons, a **V**-shaped hopper portion extending lengthwise of the car with its apex at or near the longitudinal center and between the car-trucks only, upper swinging portions adapted to be swung into several positions where they form the flat bottom of a gondola car, the upper inclined sides of an **A**-shaped discharging-bottom and the longitudinal **V**-shaped hopper, and two sets of fulcruming-blocks pivotally secured to the frame of the car—one set forming the fulcruming-blocks for the upper inclined portions when they are arranged in **A**-shaped position and the other set the fulcruming-blocks when the upper swinging portions are arranged in position to form the upper inclined portions of the **V**-shaped hopper, substantially as described.

11. In a convertible dump-car, the combination of a supporting-framework provided with downwardly and outwardly inclined side discharging-aprons, a **V**-shaped hopper portion extending lengthwise of the car with its apex arranged at or near the longitudinal center and between the car-trucks only, upper swinging portions arranged to be swung into several positions where they form the upper inclined sides of the **V**-shaped hopper and the upper inclined portions of the **A**-shaped discharging-bottom, removable end boards provided with **A**-shaped cleats on the inner faces thereof to contact the ends of and assist in holding the upper swinging sections in **A**-shaped position, swinging side boards pivotally secured at their upper edges to the frame of the car, and means for locking such swinging side boards in vertical closed position, substantially as described.

12. In a convertible dump-car, the combination of a supporting-framework provided with inclined side discharging-aprons, a **V**-shaped hopper portion formed of one fixed and

one swinging section arranged lengthwise of the car with its apex at or near the longitudinal center, a single pair of longitudinal sills intermediately arranged—one between each discharging-apron and the **V**-shaped hopper, brace-rods running from such intermediate sills to each discharging-apron and the frame of the **V**-shaped hopper, upper swinging sections arranged to be folded into several positions where they form the upper inclined sides of the **V**-shaped hopper and the **A**-shaped discharging-bottom, swinging side boards pivotally secured to the frame of the car at or near their upper edges, and means for holding such swinging side boards in locked position, substantially as described.

13. In a convertible dump-car, the combination of a supporting-framework provided with downwardly and outwardly inclined side discharging-aprons, a **V**-shaped hopper portion formed of one fixed and one swinging section arranged lengthwise of the car with its apex at or near the longitudinal center, a single pair of longitudinal sills intermediately arranged—one between each discharging-apron and the **V**-shaped hopper, brace-rods running from such intermediate sills to each discharging-apron and the frame of the **V**-shaped hopper, upper swinging sections arranged to be folded into several positions where they form the upper inclined sides of the **V**-shaped hopper and the upper portions of the **A**-shaped discharging-bottom, swinging side boards pivotally secured to the frame of the car at or near their upper edges, means for holding such swinging side boards in locking position, and removable end boards provided with inwardly-extending **A**-shaped cleats arranged to contact the ends of the upper swinging sections in their **A**-shaped position, substantially as described.
